UNITED STATES PATENT OFFICE

GEORGE HOCH, OF NEW YORK, N. Y., ASSIGNOR TO STAR CHANDELIER CO., INC., OF NEW YORK, N. Y., A CORPORATION OF NEW YORK

DESIGN FOR A GLOBE HOLDER FOR LIGHTING FIXTURES OR SIMILAR ARTICLES

Application filed January 28, 1930. Serial No. 34,317. Term of patent 3½ years.

To all whom it may concern:

Be it known that I, GEORGE HOCH, a citizen of the United States, residing at 655 Jefferson Place, New York city, in the county of Bronx and State of New York, have invented a new, original, and ornamental Design for a Globe Holder for Lighting Fixtures or Similar Articles, of which the following is a specification, reference being had to the accompanying drawing, forming part thereof.

The figure is a perspective view of a globe holder for lighting fixtures, or similar articles, showing my new design.

I claim:

The ornamental design for a globe holder for lighting fixtures, or similar articles, as shown,

GEORGE HOCH.
